CLAIM

We claim the ornamental design for a mattress, as shown and described.

DESCRIPTION

FIG. 1 is a front perspective view of a mattress in accordance with the present design;

FIG. 2 is a top view thereof;

FIG. 3 is a bottom view thereof;

FIG. 4 is a left view thereof;

FIG. 5 is a right view thereof;

FIG. 6 is a front view thereof; and

FIG. 7 is a rear view thereof.

FIG. 8 is a front perspective view of a second embodiment of a mattress in accordance with the present design;

FIG. 9 is a top view thereof;

FIG. 10 is a bottom view thereof;

FIG. 11 is a left view thereof;

FIG. 12 is a right view thereof;

FIG. 13 is a front view thereof; and,

FIG. 14 is a rear view thereof.

The dashed lines in the figures form a part of the claimed design.

1 Claim, 14 Drawing Sheets
